(57) **CLAIM**

The ornamental design for portion of a semiconductor device, as shown and described.

DESCRIPTION

FIG. 1 is a top plan view of portion of a semiconductor device, showing my new design; the opposite side being a mirror image thereof;

FIG. 2 is a front elevational view thereof;

FIG. 3 is a right side elevational view thereof; the opposite side being a mirror image thereof;

FIG. 4 is a rear elevational view thereof; and,

FIG. 5 is an enlarged fragmented rear elevational view thereof, taken along the line 5—5 in FIG. 2.

The broken lines are for illustrative purposes only and form no part of the claimed design.
